CENTRIFUGAL CASTING

William J. Braddock, Wheeling, W. Va., assignor
to Wheeling Bronze Casting Company, a cor-
poration of West Virginia

Application September 24, 1932
Serial No. 634,732

4 Claims. (Cl. 22—200)

This invention relates to the centrifugal casting of tubular members of relatively great diameter, and relates particularly to the centrifugal casting of large diameter bronze bushings.

5 In the centrifugal casting of small diameter bronze bushings but little difficulty is encountered in obtaining tubular members having an interior surface which is substantially free from oxidation and is relatively smooth. The ma-
10 chining necessary to give the tubular member a smooth, finished, interior surface is therefore relatively light, and but little metal is lost from the tubular member in placing its interior surface in such a condition of finish that the mem-
15 ber may be used as a bushing, or cut into a plu-
rality of bushings.

In centrifugally casting large diameter bronze bushings, however, difficulty is encountered in obtaining tubular castings having a relatively 20 smooth interior surface. By the term "large diameter" tubular castings, or bushings, I wish to include all such castings having an interior diameter greater than five inches. This is for the reason that above a five inch interior diameter 25 the centrifugated bronze castings tend to have a rough, and oxidized, interior, and that this undesirable tendency is increased in castings of increased diameter.

In the larger diameter centrifugal castings, for 30 example, those having an interior diameter of eight inches and more, the scaling and crack-
ing frequently extends from the interior surface such a distance into the body of the casting that a relatively great proportion of the metal of 35 the casting must be machined off in order to obtain a sound body, and a true and smooth interior surface.

Various attempts to prevent oxidation of the 40 metal during the progress of the centrifugal cast-
ing operation have proven inadequate. As ex-
amples of such unsuccessful practice, molten
glass, welding flux, and core sand have been in-
troduced into the interior of the tubular mem-
ber in the casting machine, on the theory that 45 they would serve as a protective coating for the
interior surface of the tube.

The object of my invention is to so act upon 50 the interior surface of molten metal, primarily non-ferrous metal, assuming tubular form in a centrifugal casting machine, that the metal adja-
cent the interior surface is smoothed and oxida-
tion is prevented.

A more general object of my invention is to 55 so act upon material, assuming the form of a
hollow cylinder by centrifugal casting, that a

finished tubular member having a relatively smooth interior surface is produced.

The accompanying drawing illustrates, in gen-
eralized form, exemplary apparatus for conduct-
ing the method of my invention. In the exem-
plary drawing, Figure I is a view showing a cen-
trifugal casting machine and mold in vertical 60 section, and showing in side elevation means for
acting upon the interior surface of the casting
during the progress of the centrifugal casting 65 operation; Figure II is a cross-sectional view
through the casting machine and apparatus,
taken on the line II—II of Figure I; Figure III
is a fragmentary view, in vertical section, taken
on the line III—III of Figure I, showing a suit-
able form of support for smoothing means used
in conducting the method of my invention with
tools of simple form; Figure IV is a side eleva-
tion illustrating, as an example, mechanism suit-
able for conducting the method of my invention;
and Figure V, taken on the line V—V of Figure 70
IV, shows in cross-section and on a greatly en-
larged scale a shoe suitable for use in conduct-
ing my method.

In conducting a method of centrifugally cast-
ing large diameter bronze bushings, in accordance 80
with my procedure, a casting machine 1, contain-
ing a liner or mold 2, is caused to revolve rapidly
about its axis. The bronze, in liquid condition,
is introduced by means of a removable pouring 85
basin, and the basin is removed from before the
open end of the casting machine.

Immediately upon removal of the pouring 90
basin, supports 3 for the smoothing tools may be
brought into position before the open end of the
casting machine. As shown in Figure I of the
drawing, these smoothing tools comprise a rod 4,
carrying a smoothing shoe 5, and a tube 6 for
conveying water, or other suitable fluid to the 95
smoothing shoe.

The operator, by moving shoe 5 backwardly and
forwardly, causes it to traverse the interior sur-
face of the casting longitudinally. As the casting
machine is simultaneously revolving about its
axis at relatively high speed, the shoe is thus
repeatedly brought to bear upon the entire inter-
ior surface of the casting. In addition to trav-
ersing the smoothing shoe over the interior sur-
face of the casting, the operator causes it to bear
down upon the molten metal, so that it exerts a 105
compacting effect on the metal adjacent the in-
terior surface.

It will be noted, particularly by reference to
Figures II and V of the drawing, that the metal-
contacting face of smoothing shoe 5 is desirably 110

formed on an irregular curve, with the trailing portion of the face formed on a radius less than that upon which the edge portion presented to the rotating movement of the machine and mold 5 is formed. The shoe also has its greater weight to the trailing side of the mounting, so that its inherent tendency is to rotate counter to the direction of rotation of the machine and the casting. This conformation tends to prevent the 10 shoe from ploughing deeply into the metal at the beginning of the operation, when the metal is in its condition of higher liquidity.

It is possible that the smoothing shoe may be made of various materials. The material which 15 I have found most satisfactory for the shoe is hard wood. Since, during the casting operation, the shoe 5, may be sprayed with a cooling liquid from pipe 6, the surface of the shoe which is presented to the molten metal chars slowly under 20 the conditions of the process. This slow charring of the shoe possesses positively advantageous features. Thus, the charring causes the metal-contacting region on the operating face of the shoe to wear away to such extent as to assume approximately 25 the radius of curvature of the casting bore. This effect avoids the necessity of using a number of shoes of varied curvature, predetermined with reference to the diameter of the various 30 castings with which they are used. The slow charring also gives the operating surface of the shoe the qualities of an instrument for fine smoothing.

In practice I have found that a metal shoe, as 35 for example a shoe made of iron, may be used. An iron shoe, however, does not conform the contacting region of its operating surface to the bore curvature of the casting by charring. There is also a tendency, present at the beginning of the process, for an iron shoe to stick to, and pick 40 up, the metal of the casting. If a wooden shoe be used during the initial stages of the operation, a metal shoe, having its operating surface appropriately curved, may be used with satisfaction during the concluding stages of the operation.

45 It is probable that fibre composition shoes, having the slow-charring property of hard wood, may prove wholly as satisfactory in service as those made of wood.

In addition to its function of preventing combustion of a combustible shoe, and regulating the 50 rate of charring on the operating face of the shoe, the spray of cooling liquid performs the additional function of chilling the metal of the casting, and expediting its congelation.

55 As a variation of my method, I may use a shoe extending the entire length of the casting, and bring pressure to bear on it. For some reason, or reasons, this practice is less satisfactory than the use of a smaller shoe moved forwardly and backwardly in the casting. It does, however, to an appreciable extent, improve the interior surface 60 of a centrifugal casting in comparison with an operation in which no smoothing pressure is exerted on the interior surface of the casting.

65 Figure IV of the drawing shows an alternative, exemplary, mounting for the smoothing tool and spray tube. In this arrangement the spray tube 70 7 serves also as a mounting rod for the shoe 5, and the shoe is so mounted thereon as to provide a channel or channels for the passage of cooling liquid to and along the surface of the shoe. The tube 7 is mounted for direct hand reciprocation in holders 8, carried by threaded stems 9. Stems 75 9 may be caused to rotate by means of worms 10,

carried by a rotatable lay shaft 12 and co-operating with gears 11 on the stems.

In use of this arrangement, the tubular shoe-carrying rod 7 is reciprocated directly by hand, and the shoe is caused to bear down on the casting 80 by rotating lay shaft 12.

Various other mechanical installations, more or less automatic in their nature may be employed. By use of the device shown in Figure IV, however, I have found that any mechanical means are less desirable, at the beginning of the casting operation, than a simple hand operation, such as that indicated in Figures I and II. This is for the reason that a simple hand operation permits the operator to get the "feel" of the work. The operator having this "feel" may avoid the exertion of too great pressure on the casting while the metal is in its initial condition of higher liquidity.

95 While my invention is directed primarily to improvement in the centrifugal casting of large diameter bronze bushings, it may be employed in other applications of the centrifugal casting principle. For example, it has been found valuable in the centrifugal casting of sewer piping formed 100 of cementitious material. In that use, it similarly prevents roughness and fissures on the interior, or bore, surface of the casting.

I claim as my invention:

1. In the art of centrifugal casting, the herein 105 described method of obtaining a sound body adjacent the bore of a tubular member of non-ferrous metal and a true and relatively smooth bore surface of the tubular member, which comprises traversing throughout the greater proportion of the casting operation a smoothing tool co-operatively curved with respect to the bore curvature of the tubular member in process of formation and having the approximate qualities of hard wood longitudinally of the interior surface of the 115 fluid metal centrifugated to form the tubular member, exerting pressure on the bore surface by means of said smoothing tool as it is traversed, and exerting on the smoothing tool in its use a cooling effect to retard combustion of the 120 smoothing tool.

2. In the art of centrifugal casting, the herein 125 described method of obtaining a sound body adjacent the bore of a tubular member of non-ferrous metal and a true and relatively smooth bore surface of the tubular member, which comprises traversing throughout the greater proportion of the casting operation a smoothing tool 130 co-operatively curved with respect to the bore curvature of the tubular member in process of formation and having the approximate qualities of hard wood longitudinally of the interior surface of the fluid metal centrifugated to form the tubular member, exerting pressure on the bore 135 surface by means of the smoothing tool as it is traversed, and supplying a cooling liquid to the surface of the smoothing tool.

3. In the art of centrifugal casting, the herein 140 described method of obtaining a sound body adjacent the bore of a tubular member of non-ferrous metal and a true and relatively smooth bore surface of the tubular member, which comprises traversing a smoothing tool having an operating surface co-operatively curved with respect 145 to the bore curvature of the tubular member in process of formation longitudinally of the interior surface of the fluid metal centrifugated to form the tubular member, exerting pressure on the bore surface by means of the smoothing tool as it is traversed, and supplying a cooling liquid 150

in the path of movement of the smoothing tool. 4. In the art of centrifugal casting, the herein described method of obtaining a sound body adjacent the bore of a tubular member of non-
5 ferrous metal and a true and relatively smooth bore surface of the tubular member, which comprises traversing throughout the greater proportion of the casting operation a smoothing tool having an operating face co-operatively curved
10 with respect to the bore curvature of the tubular

member in process of formation and controllably combustible under the temperature conditions of the process longitudinally of the interior surface of the fluid metal centrifugated to form the tubular member, exerting pressure on the bore surface 80 by means of said smoothing tool as it is traversed, and controlling combustion of the smoothing tool by exerting a cooling effect on the smoothing tool in its use.
